UNITED STATES PATENT OFFICE.

JAMES WILKINSON, OF SCHENECTADY, NEW YORK, ASSIGNOR TO GENERAL ELECTRIC COMPANY, A CORPORATION OF NEW YORK.

DAMPER-REGULATOR.

1,093,161.

Specification of Letters Patent. Patented Apr. 14, 1914.

Application filed May 14, 1913. Serial No. 767,491.

To all whom it may concern:

Be it known that I, JAMES WILKINSON, a citizen of the United States, residing at Schenectady, county of Schenectady, State of New York, have invented certain new and useful Improvements in Damper-Regulators, of which the following is a specification.

The present invention relates to steam generating plants and has for its object to provide an improved mechanism for regulating the position of a damper located in the flue or stack through which the exhaust gases escape to the atmosphere so that the boiler will deliver the proper amount of vapor at the predetermined pressure.

In the accompanying drawing Figure 1 illustrates a boiler plant fitted with my improved mechanism, and Fig. 2 is a detail view of a suitable device for creating a pressure difference in response to changes in the rate of flow of fluid from the boiler.

1 indicates a boiler or vapor generator of any suitable construction which is heated by a coal fire or other means indicated at 2. The exhaust gases after heating the boiler pass to atmosphere through the stack or flue 3. Steam or other vapor passes from the boiler by the main 4 to engines or other consumption devices.

Situated at some convenient point with respect to the boiler is a diaphragm 5 contained in a casing 6. Steam or other vapor under pressure is conveyed to the under side 35 of the diaphragm by the pipe 7. Attached to or supported by the upper side of the diaphragm is a device 8 that forms an adjustable fulcrum sensitive to boiler pressure for the movable member 9 which in the present 40 embodiment of my invention takes the form of a lever. At one end of the lever is a fulcrum 10 whose position is normally fixed. This lever is given a constant tendency to move downward against the action of the 45 vapor pressure by suitable means, such as the spring 11 or spring and weight 12. By changing the tension of the spring by its adjusting nut or sliding the weight on the lever the force acting in opposition to the 50 vapor pressure can be changed. The spring 11 should be so calibrated and arranged as to compensate for the complete shifting of the mercury from minimum to maximum deflection. As the mercury is deflected to the 55 left the spring should gradually yield caus-

ing the lever 9 and parts associated therewith to assume intermediate positions. Conversely as the mercury flows backward toward a condition of equilibrium in the mercury containing vessel the lever should move 60 gradually upward. In other words, the resistance of the spring should vary with changes in displacement of the mercury in the vessel with respect to the fulcrum 10. Without the spring or some equivalent 65 means the lever would move its full distance whenever the mercury in the vessel was so distributed as to overbalance the opposing force of the diaphragm.

Mounted on the lever or so related thereto 70 that it affects the same is a vessel 13 containing a U-shaped chamber which contains mercury 14 or some other fluid heavier than the vapor generated by the boiler. As the mercury is displaced from one leg to the 75 other of the chamber it will cause a greater or less deflection of the free end of the lever about its fulcrum 10. That is to say, as the mercury is forced from the right into the left-hand part of the chamber its weight 80 will overcome the vapor pressure acting through the diaphragm and move the free end of the lever downward. When permitted to flow back into the right-hand part of the chamber the vapor pressure will lift 85 the free end of the lever to a greater or less amount. To state the matter broadly and in another way, the mercury forms an adjustable weight on the lever 9 whose effective action thereon varies in response to 90 changes in the rate of flow of vapor from the generator.

Since the ultimate object of the apparatus is to change the position of a regulator such as a damper 15 in the flue to vary the effective draft on the fire in accordance with variations in the amount of fluid flowing through the main as well as to adjust it subject to changes in pressure, I mount in the main an agent of any suitable character 95 by which a pressure difference is created whose value changes with changes in the rate of flow of the vapor passing through the main and which is transmitted to the mercury containing vessel. As an example, I have shown 100 a plug 16 having orifices 17 facing the moving column of fluid and one or more orifices 18 facing in the opposite direction. Such a device operates on the principle of a Pitot tube. With such devices the openings 17 are 105 110

commonly referred to as the leading orifices and the openings 18 as trailing orifices. The difference in fluid pressure due to the action of the vapor column and the agent 5 is conveyed to the legs of the vessel 13 by the pipes L and T, the former being connected to the leading orifices in the agent and the latter to the trailing orifice. Since the vessel moves with the lever 9 these pipes are 10 each provided with a flexible connection 19 which permits this action to take place without opposing undue opposition thereto.

The damper 15 may be operated by different means. As shown it is provided with an 15 arm carrying a segment of a gear 20 that meshes with a rack 21 attached to the upper end of a piston rod 22.

23 indicates a motor comprising a cylinder and a piston, the latter being attached to the 20 rod 22. The motor is controlled by a pilot valve or controller 24 which is attached to and moved by the lever 9. Surrounding the valve is a ported sleeve 25 which is attached at its upper end to a lever 26 by a pin and 25 slot connection or equivalent means. One end of this lever has a fixed fulcrum 27, the other end being suitably attached to the piston rod 22. The rod, sleeve and lever 26 form a follow-up device to prevent over 30 travel of the motor piston. Pipe 28 conveys fluid under pressure such as steam, water, air or liquid to the pilot valve and pipes 29 and 30 the exhaust therefrom. Pipes 31 and 32 convey fluid to and from the pilot valve 35 and the motor cylinder.

The action of my improved regulating mechanism is as follows: Assuming that the 40 rate of flow remains constant an increase or decrease in boiler pressure will act on the diaphragm 5 and change the vertical position of the fulcrum 8. As the free end of the lever rises or falls the position of the pilot valve will be correspondingly changed. This admits fluid to one side or the other of 45 the piston and as it moves it adjusts the damper 15 to increase or decrease the effective outlet area of the flue 3 and hence the draft on the fire. When the piston rod 22 moves it adjusts the sleeve 25 through the 50 lever 26 to close the ports leading to the motor and in this manner to stop the piston. Assuming now that the boiler pressure remains constant and the rate of flow of vapor through the main 4 increases or decreases, a certain pressure difference corresponding to 55 said rate of flow will be conveyed from the agent through the pipes L and T to the vessel 13 and the mercury will be displaced to a greater or less extent from one leg to the other. Assuming that the rate of flow increases mercury will be forced from the right to the left hand leg of the vessel and this shifts the center of gravity of its mass farther from the fulcrum 10 of the lever. This results in moving the pilot valve downward

by the amount of spring tension released, permitting fluid under pressure to enter the motor from the pipe 28 and raise its piston and in so doing open the damper 15 wider and increase the draft on the fire. As before stated the movement of the rod 22 and lever 26 will adjust the sleeve 25 and prevent over travel. If the flow decreases the damper will be closed by the same means acting in the opposite direction and to a 75 greater or less extent.

Of course a change in boiler pressure may and probably would be coincident with a change in the rate of flow but to facilitate an 80 understanding of my invention I have described the operations separately.

My improved mechanism has the advantage that it responds instantly to variations in demand and does not require a decided change of operating conditions to take place 85 before the proper remedy is applied. As a result of this the boiler losses in the plant will be decreased for each boiler will perform its proper share of the work instead of one doing a larger and another a small 90 part. My improved arrangement is of particular importance where a number of boilers supply vapor in multiple to a header or receiver from which the vapor flows to the 95 consumption devices.

In accordance with the provisions of the patent statutes, I have described the principle of operation of my invention, together with the apparatus which I now consider to represent the best embodiment thereof; but I 100 desire to have it understood that the apparatus shown is only illustrative, and that the invention can be carried out by other means.

What I claim as new and desire to secure by Letters Patent of the United States, is:— 105

1. In combination, a boiler, a source of heat, a flue for the exhaust gases, a regulator for the draft due to said flue, a main for conveying vapor from the boiler, a means sensitive to changes of pressure of 110 the vapor in the boiler for adjusting the regulator, and a means sensitive to changes in the rate of flow of vapor through the main from the boiler which also adjusts the regulator. 115

2. In combination, a boiler, a source of heat, a flue for the exhaust gases, a regulator for the draft due to said flue, a motor for moving the regulator, a controller therefor, a main for conveying vapor from the 120 boiler, a means sensitive to changes of pressure in the boiler which acts on the controller, and a means responsive to changes in the rate of flow of vapor through the main which also acts on the controller. 125

3. In combination, a boiler, a source of heat, a flue for the exhaust gases, a regulator for the draft due to the flue, a main for conveying vapor from the boiler, a movable member which determines the position 130

of the regulator, a means sensitive to changes in the rate of flow of fluid through the main, and a means sensitive to changes in boiler pressure, both of said last mentioned means coöperating to move said member.

4. In combination, a boiler, a source of heat, a flue for the exhaust gases, a regulator for the draft due to said flue, a main for 10 conveying vapor from the boiler, a means sensitive to the boiler pressure, a movable member having a fulcrum which is supported by the means, a fluid containing vessel that acts on the member to move it, an 15 agent adapted to cause a pressure difference which varies as the rate of flow of vapor through the main changes and communicates this pressure difference to the vessel to displace the fluid therein and cause it to 20 move the member, and means responsive to the movements of the member for adjusting the regulator.

5. In combination, a boiler, a source of heat, a flue for the exhaust gases, a regulator for the draft due to said flue, a main for 25 conveying vapor from the boiler, an agent in the main which causes a pressure difference dependent upon the rate of flow of vapor through the main, a means sensitive 30 to changes in boiler pressure, a device connected to the agent and movable subject to the pressure difference due to the agent, a member jointly acted upon by the device and said boiler pressure responsive means, 35 and mechanism responsive to movements of the member to adjust the regulator.

6. In combination, a boiler, a source of heat, a flue for the exhaust gases, a regulator for the draft due to said flue, a main for 40 conveying vapor from the boiler, an agent in the main which causes a pressure difference dependent upon the rate of flow of vapor in the main, a means sensitive to boiler pressure, a movable member having a fixed 45 pivot, a fulcrum therefor carried by the pressure sensitive means, a vessel connected to the agent and mounted on the member, which contains liquid whose center of gravity is displaced with respect to the 50 pivot as the rate of flow of vapor through the main changes, a motor for adjusting the regulator, a controller therefor which is

connected to the member, and a follow-up device to prevent over travel of the motor.

7. In combination, a boiler, a source of heat, a flue for the exhaust gases, a regulator for the draft due to said flue, a main for 55 conveying vapor from the boiler, an agent in the main which causes a pressure difference dependent upon the rate of flow of vapor in the main, a means sensitive to boiler pressure, a lever which has a fixed pivot, a fulcrum for the lever moved by said means, 60 a vessel having a chamber containing liquid, the said vessel being mounted on the lever and connected to the agent so that the liquid will be displaced from one part of the chamber to the other as the rate of flow of vapor 65 in the main changes to vary the load on the lever, a motor connected to the regulator for moving it, a pilot valve for the motor which is connected to the lever, a ported sleeve surrounding the pilot valve, and a lever that is 70 attached to the sleeve and to a moving part of the motor to prevent over-travel of the 75 motor piston.

8. In combination, a boiler, a source of heat, a flue for the exhaust gases, a regulator for the draft due to the flue, a main for 80 conveying vapor from the boiler, a means sensitive to changes of pressure of the vapor, a means sensitive to changes in the rate of flow of vapor through the main, a member which is acted upon jointly by said 85 means to adjust the regulator, and a yielding means that acts on said member.

9. In combination, a boiler, a source of heat, a flue for the exhaust gases, a regulator for the draft due to the flue, a main for 90 conveying vapor from the boiler, a means sensitive to changes of pressure of the vapor, a means sensitive to changes in the rate of flow of vapor through the main, a member which is acted upon jointly by said 95 means to adjust the regulator, and an adjustable spring that acts on said member in opposition to the pressure sensitive means.

In witness whereof, I have hereunto set 100 my hand this 12th day of May, 1913.

JAMES WILKINSON.
